OR D 15,042

No. 15, 042

June 3, 1884

UNITED STATES PATENT OFFICE.

JOSEPH A. READ AND JOHN E. McMENOMAY, OF PHILADELPHIA, PA.

DESIGN FOR A FIRE-PLACE FRONT.

SPECIFICATION forming part of Design No. 15,042, dated June 3, 1884.

Application filed April 21, 1884. Term of patent 7 years.

To all whom it may concern:

Be it known that we, JOSEPH A. READ and JOHN E. McMENOMAY, citizens of the United States, and residents of Philadelphia, Pennsylvania, have invented a certain new and original Design for Fire-Place Fronts, of which the following is a specification.

Our design is fully shown in the accompanying photograph.

- 10 The central panel comprises a border ornamented with a zigzag bar and a stem with leaves and blossoms. The body of the panel has a central A-shaped band ornamented with a leafy stem, the lower corners of the body 15 having segmental ornaments, above which is a central ornament composed of stems, leaves, and blossoms conventionally treated. The upper corners of the body have ornamentation of a foliated character, as fully shown. The 20 border of the front piece has an inner band with small ornaments of a trefoil character,

and an outer band with zigzag bars and leafy stems of the same general character as those on the border of the body.

We claim—

- 25 1. The design for the central panel of a front piece for fire-places, said design comprising the border, central band and ornament, and corner ornamentation, as shown and described.
2. The design for the border of a front piece 30 for fire-places, said design comprising the inner and outer bands ornamented as shown and described.

In testimony whereof we have signed our names to this specification in the presence of 35 two subscribing witnesses.

JOSEPH A. READ.
JOHN E. McMENOMAY.

Witnesses:

JOHN E. PARKER,
HARRY SMITH.
